F. S. RATCLIFFE

WRENCH

Filed June 5, 1920

UNITED STATES PATENT OFFICE.

FRANK S. RATCLIFFE, OF MILWAUKEE, WISCONSIN; IRA M. JONES, ADMINISTRATOR OF SAID FRANK S. RATCLIFFE, DECEASED, ASSIGNOR TO EMILY RATCLIFFE, OF MILWAUKEE, WISCONSIN.

WRENCH.

Application filed June 5, 1920. Serial No. 386,907.

To all whom it may concern:

Be it known that I, FRANK S. RATCLIFFE, a citizen of the United States, and resident of Milwaukee, in the county of Milwaukee and State of Wisconsin, have invented certain new and useful Improvements in Wrenches; and I do hereby declare that the following is a full, clear, and exact description thereof.

- 10 My invention relates to new and useful improvements in wrenches for turning nuts, bolts or other work objects, and more particularly of that type including a pair of slidably connected jaw carrying shanks, 15 having means for locking the shanks against relative movement in selective relative positions thereof, whereby to procure proper engagement of the jaws with the faces of the work object.
- 20 It is primarily the object of my invention to provide a commercially practical wrench of this character, which may be operated in a most convenient and rapid manner, and to this end it is more specifically my object to 25 provide a wrench wherein the locking mechanism for the jaw shanks is automatically operative in the working stroke of the wrench, and inoperative in the retracting stroke of the wrench to procure a fresh grip 30 on the work object, and wherein means is provided for automatically urging the jaws to snug engagement with the wrench faces of the work object, thus providing for an exceedingly ready initial adjustment of the 35 wrench for the size of work object on which it is to operate, and providing for an automatic pump action of the wrench on the work member in turning the same, whereby to procure the operative advantages of the 40 ratchet type of wrench, avoiding the necessity of removing the wrench from the work object upon each turning impulse when operating in a restricted space.

Being cognizant of the severe conditions 45 of structure which must be satisfied in the provision of a tool of this character, it is an important object of my invention to provide a structure embodying the aforesaid advantages, which comprises a minimum number 50 of parts, and which has its major parts so arranged as to avoid the occurrence of any weak points in the structure of the wrench under the stresses to which it would be subjected in use, and wherein the mecha-

nism of the wrench is entirely housed by 55 the natural disposition of its parts.

With the above and other objects and advantages in view, my invention resides more particularly in the novel combination, formation and arrangement of parts herein-after described and more particularly pointed out in the appended claims.

In the accompanying drawings:

Fig. 1 is a longitudinal sectional view 65 through a wrench embodying my invention;

Fig. 2 is a transverse sectional view there-through on a plane indicated by the line 2-2 of Fig. 1;

Fig. 3 is a transverse sectional view there-through on a plane indicated by the line 70 3-3.

Referring now more particularly to the accompanying drawings, the wrench therein shown, and constituting one embodiment of my invention, which is adapted more particularly for the general uses of the ordinary monkey wrench, comprises a tubular body shank 5 which is oblong in cross section, and has a laterally extending jaw 6 formed integrally at one end. The wider sides of the body shank are extended at the other end thereof to provide pivot ears for the inner end portion of a handle 7, said inner end portion of the handle being shaped to fit therebetween and to close the adjacent end 80 of the channel of the body shank. The handle is connected with the ears by a large pivot bolt 8, which is sufficiently large to meet the shearing stresses imparted thereto in the operation of the wrench, and this 85 pivot bolt is located at one side of the axis of the body shank. The inner corners of the handle member are adapted to abut the adjacent ends of the narrower sides of the body shank, and thus restrict the pivotal movement of the handle member within a relatively small range. A shank 9 is slidably mounted within the tubular shank 8 from the outer end of said shank, and this 90 slideable shank carries a jaw 10 cooperating with the jaw 6, for engaging the opposed wrench faces of a work object. The slideable shank 9 is provided with a longitudinal channel 11 extending from its inner end to a point adjacent its outer end, this channel 11 thus 95 communicating with the channel of the body section 5, and disposed in said channels is a fairly strong retractile spring 12, which has

100
105

one end secured in the outer end of the channel of the slidable shank and jaw, and has its other end connected with the body shank preferably by attachment to the inner end 5 of the handle 7, this latter point of attachment being disposed at one side of the pivot axis of the handle. Thus, the work engaging jaws of the wrench are resiliently urged together for proper snug engagement with 10 the faces of a work member to which the wrench may be placed.

For holding the shank members against relative outward movement when desired to thus procure the wrench action, the inner 15 surface of the body shank 5 adjacent the jaw 6 is recessed at 13, said recess extending in the present instance into the jaw, and this recess is provided with an oblique cam surface which is afforded in the present in- 20 stance by a wear plate 14 of hard metal set into the recess. The opposed side face of the slidable shank 9 is suitably hardened to provide a coacting clutch surface, and disposed in the recess for engagement with this 25 clutch surface are a pair of rollers 15 which are mounted on a pin 16 connected with the outer end of a spring arm 17 which extends longitudinal of the body shank through a groove 18 in the adjacent inner face of the 30 body shank, said spring arm being secured to the corner portion of the handle member which is remote from its pivotal axis. The permitted degree of pivotal movement of the handle member 7 is such with respect to 35 its connection with the arm 17, that, when the handle is rocked in a clockwise direction, the arm 16 will withdraw the rollers from the clutch surfaces, thus rendering the clutch inactive, and permitting the sliding 40 jaw 9 to be drawn outwardly against the action of the spring 12, and when the handle 7 is swung in a counter-clockwise direction, it will engage the rollers with the clutch 45 surface to thus render the clutch effective to prevent outward movement of the sliding shank, the resilience of the spring arm 17 serving to insure this snug engagement of the rollers for the clutch action.

Thus, in operation of the wrench, the 50 handle 7 and the jaw head of the sliding shank may be grasped, and these parts drawn apart to engage the wrench on a nut or other object to be turned, the jaws springing together to engage the work when the 55 parts are released. Rocking movement of the handle 7 will first insure engagement of the rollers with the clutch surface, and the sliding shank being thus held, continued turning pressure on the handle will effect the 60 turning operation of the wrench. In reverse movement, to procure a fresh grip on the work object, a reverse pressure will be imparted to the handle with the jaws still remaining about the work object, and the 65 clutch rollers will be retracted from their

clutching position, and the wrench then turned idly about the work object, the slid- 70 able shank moving into and out of the body shank under influence of the spring to pro-
vide for proper engagement with the wrench faces of the work object in effecting the succeeding turning movement.

I have thus provided an exceedingly sim- 75 ple, strong and efficient wrench which is ca-
pable of reciprocating operation in the man-
ner of the ordinary ratchet wrench, yet
which is instantly adaptable for any size
of work object within a general range.

At the same time, the present wrench may be advantageously applied to any of the uses 80 of the ordinary monkey wrench, and is instantly adjustable for any desired size of work object.

The present wrench structure eliminates 85 various of the parts heretofore employed in standard wrenches, and employs an equally simple, instantly operable adjusting means. All of the working parts of the wrench are completely housed by their natural disposi- 90 tion within the tubular body shank 5 which forms a casing, and my improved wrench will thus prove exceedingly durable in nature, being free from liability of break-
age of minor parts. Attention is also par- 95 ticularly directed to the fact that the three major wrench parts, that is, the body shank, sliding shank and handle are connected in such manner as to procure adequate strength to meet the severest conditions of use to 100 which a wrench would be subjected, and it is further noted that the sliding shank is posi-
tively held by the channel surface of the body shank against movement in any lateral direction, and hence, transverse stresses ap- 105 plied, as in hammering, to the slidable jaw, would not affect the holding mechanism for the jaw shank.

While I have shown and described a preferred embodiment of my invention, it will be apparent that the novel 110 principles embodied may be carried out in a number of forms, and that the present structure is to be treated merely as one ex-
emplification of my invention, and that va- 115 rious changes and modifications of structure and arrangement may be employed to meet different conditions of use and manufacture, without departing in any manner from the spirit of my invention.

I claim:

1. A wrench comprising a pair of slidably connected shanks, work engaging jaws carried by said shanks, a handle pivotally connected with one of the shanks, means oper- 125 able by pivotal movement of the handle in one direction for locking the shanks against relative movement, said means being releasable by movement of the handle in the opposite direction, cooperating means on the handle and one shank for limiting the piv- 130

otal movement of the handle, and means for normally urging the jaws of the said shanks together.

2. A wrench comprising a tubular body shank, a work engaging jaw carried rigidly thereby, a shank slideable in the tubular body shank, a work engaging jaw carried by said slideable shank, a handle carried by the tubular body shank and having limited lateral movement with respect thereto, and means movable upon movement of the handle for securing the slideable shank against movement in the main tubular shank.

15 3. A wrench comprising a tubular body shank, a work engaging jaw carried thereby, a shank slideable in the tubular body shank, a work engaging jaw carried by said slideable shank, a handle carried by the tubular body shank and having limited lateral movement with respect thereto, and lock means including a member adapted for wedging engagement with the slideable shank, said means being operable by movement of 25 the handle.

4. A wrench comprising a tubular body shank, a jaw carried thereby, a shank slideably connected with the body shank and provided with a longitudinal channel communicating with the channel of the body shank, a retractile spring extending in the channels of both shanks and connected at its ends with the shanks, a handle connected with the end of said body shank remote from the jaw carried thereby and having a limited movement with respect thereto, and means for holding the slideable shank against movement with respect to the body shank upon movement of the handle 30 in one direction and for permitting movement of said slideable shank with respect to the body shank upon movement of the body shank in a reverse direction.

5. A wrench comprising a tubular body shank, a jaw carried by said shank, a shank slideable in one end portion of the body shank, a jaw carried by said slideable shank, a handle pivotally connected with and closing the other end of the body shank, 45 means yieldably urging the slideable shank to movement into the body shank, and

means operable by pivotal movement of the handle for preventing relative movement of the shanks.

6. A wrench comprising a tubular body shank, a jaw carried by said shank, a shank slideable in one end portion of the body shank, a jaw carried by said slideable shank, a handle pivotally connected with and closing the other end of the body shank, means 55 yieldably urging the slideable shank to movement into the body shank, said shanks being provided with opposite clutch portions, and a member connected with the handle for movement thereby and cooperating with 60 said clutch portions to hold the shanks against relative movement upon movement of the handle in one direction.

7. A wrench comprising a tubular body shank having its inner surface provided with a longitudinal groove, a jaw carried by said shank, a shank slideable in the tubular body shank, a jaw carried by said slideable shank, a handle pivotally connected with the outer end portion of the body 70 shank, an arm extending from the handle through the groove of the body shank, a clutch roller carried by said arm, and opposed clutch faces on said shanks engageable by said roller to prevent relative movement of the shanks upon pivotal movement 75 of the handle in one direction.

8. A wrench comprising a tubular body shank having its inner surface provided with a longitudinal groove, a jaw carried 80 by said shank, a shank slideable in the tubular body shank, a jaw carried by said slideable shank, a handle pivotally connected with the outer end portion of the body shank, a spring arm extending from the 85 handle through the groove of the body shank, a clutch roller carried by said arm, and opposed clutch faces on said shanks engageable by said roller to prevent relative movement of the shanks upon pivotal 90 movement of the handle in one direction.

In testimony that I claim the foregoing I have hereunto set my hand at Milwaukee, in the county of Milwaukee and State of Wisconsin.

FRANK S. RATCLIFFE.
